UNITED STATES PATENT OFFICE.

NANNIE K. HUNT, OF ADOLPHUS, KENTUCKY.

COLLAPSIBLE SHIPPING CONTAINER.

1,424,099.

Specification of Letters Patent. Patented July 25, 1922.

Application filed March 21, 1922. Serial No. 545,553.

To all whom it may concern:

Be it known that I, NANNIE K. HUNT, a citizen of the United States, residing at Adolphus, in the county of Allen and State 5 of Kentucky, have invented certain new and useful Improvements in Collapsible Shipping Containers, of which the following is a specification, reference being had therein to the accompanying drawings.

10 This invention relates to collapsible shipping containers and it has for its object to provide a device of this character made up of a plurality of nested sections and a plurality of sectional braces, the latter being 15 adapted to be taken apart and packed in the sections of the container in shipment.

In the accompanying drawing:

Fig. 1 is a view in side elevation of a collapsible container with the brace presenting 20 a face view;

Fig. 2 is a side elevation of a collapsible container with the braces presented in edge view; and

Fig. 3 is a perspective view of some of the 25 elements of the brace.

The container may be of any desired shape, such for example, as round or square, and it consists of a plurality of sections as, for example, 5, 6, 7, 8 and 9, the section 9 30 constituting a bottom and the remaining sections being of successively greater diameter and slightly tapering so that when the uppermost section 5 is grasped and drawn upwardly all of these sections will be 35 brought into engagement with each other, the lower edge of section 8 engaging about the upper edge of section 9 and so on. To hold these sections in the position illustrated, I employ braces made up of a plurality of 40 plates 10, 11, 12, 13 and 14. It will, of course, be understood that these braces may be of any length and may embody as many sections as desired. The lowermost section 14 is provided with a slot or eye 15 which receives an 45 extension 16 of the section 13. Each of the other sections, except the upper section 10, is provided with a corresponding extension 16 which enters a corresponding eye 15 of said other section. The uppermost section 50 10 is provided only with the extension 16 and not with the eye. The upper and lower sections 5 and 9 of the container carry hooks 17 and 18, respectively, which engage with eyes 19 and 20 upon the uppermost plates 10 and 55 14, respectively. Thus when the several sec-

tions of the braces are brought into engagement with each other, as illustrated in Fig. 2, they serve to hold the sections of the container in extended condition or in the position shown in the drawing. By disengaging 60 the hooks 17 and 18 from the eyes 19 and 20 the braces may be removed and the sections 5 to 9 collapsed. The several sections of the braces may then be disengaged from each other and placed in a collapsed container for shipment with said container. It is a well known fact that it is highly desirable to provide a simple container which may be collapsed so that the empty containers when being returned to their owners will 70 take up but little room. The simple annular segments 5 to 9 provide a shipping container which may be manufactured at a very small cost and the braces herein shown and described provide simple and efficient means 75 for holding said annular elements in their extended position, while at the same time they may be readily brought to small compass when it is desired to collapse the structure and return it to its owner.

It is to be understood that the invention is not limited to the precise construction set forth but that it includes within its purview whatever changes fairly come within either the terms or the spirit of the appended 80 claims.

Having described my invention what I claim is:

1. A collapsible container comprising a plurality of annular interengaging elements 90 and a plurality of braces, each of said braces comprising a plurality of sections, means for connecting the several sections of said braces detachably together in such manner that when said sections are connected the braces 95 are vertically rigid, said means comprising slots formed in some of the sections and offset projections upon other of the sections engageable in said slots and interengaging elements between the uppermost and lowermost sections of the container and the uppermost and lowermost sections of the braces.

2. A collapsible container comprising a plurality of annular sections, each section 105 being successively greater in diameter than the section below and being adapted to engage therewith and a plurality of braces each of said braces comprising a plurality of sections some of which have slots formed 110

therein and others of which have projections formed thereon adapted to engage in said slots in such manner that when the said 5 projections are engaged in the slots the braces are vertically rigid, eyes formed upon the uppermost and lowermost sections of the braces and hooks carried by the uppermost

and lowermost sections of the container adapted to engage in the eyes of the braces as and for the purposes set forth. 10

In testimony whereof I hereunto affix my signature.

NANNIE K. HUNT.
